UNITED STATES PATENT OFFICE.

CHRISTOPHER G. GUIGNARD, OF COLUMBIA, SOUTH CAROLINA.

AUTOMATIC CUTTER FOR CUTTING A TUBULAR GAUZE COVERING FOR SANITARY NAPKINS.

Application filed June 6, 1924. Serial No. 718,416.

To all whom it may concern:

Be it known that I, CHRISTOPHER G. GUIGNARD, a citizen of the United States, residing at Columbia, in the county of Rich-
5 land and State of South Carolina, have in-
vented a new and useful Automatic Cutter
for Cutting a Tubular Gauze Covering for
Sanitary Napkins, of which the following is
a specification.

10 The object of my invention is to provide
an automatic cutter which is provided with
a novel resilient operating mechanism
whereby the cutting knife will remain in a
retracted position when a knot or other ob-
15 struction is encountered so that there will
be no possibility of choking the knife with
the material as may occur with a revolving
type of knife. It is also my object to pro-
vide the novel combination and arrange-
20 ment of parts disclosed in the accompany-
ing drawings, in which—

Figure 1 is a side elevation of the invention in use;

Fig. 2 is a top plan of my invention;
25 Fig. 3 is a section on line 3—3 of Fig. 1;
Fig. 4 is a section on line 4—4 of Fig. 2;
Fig. 5 is an enlarged detail of a modified
form of cam; and

Fig. 6 is an edge or face view of the
30 mechanism illustrated in Fig. 5.

Like characters of reference indicate like
parts in each of the several views.

Referring to the accompanying drawings
I provide a table or supporting frame 1
35 having a top 2 and an apron 3, as shown in
Fig. 1. I provide bearings 4 for the hori-
zontal shaft 5 which is driven by chain C
from a suitable source of power, such as the
severing machine described in a co-pending
40 application Serial 718,415 filed June 6, 1924.
I provide a pedestal 7 carrying a hinged or
oscillatory bearing 9 in which the shaft 10
is mounted. I also provide a pedestal 8
45 carrying upright standards 12 and provide
springs 13 which press on the bearing 11
in which the shaft 10 is mounted to normally
press the rubber-covered friction roller 14
toward the bottom friction roller 6 mounted
50 on shaft 5. I provide a gear 16 on shaft 17,
as shown in Figs. 1 and 2, which gear
meshes with gear 15 on shaft 5 whereby ro-
tary motion is transmitted from shaft 5 to
shaft 17 which latter shaft also carries the

cam 18. Cam 18 contacts with roller 19
mounted in the bifurcated end 20 of the
55 slideable rod 21 which is mounted in the
sleeve 22 and is resiliently pressed towards
cam 18 by the spring 25 within sleeve 22.
Sleeve 22 is provided with a closed end 24
and a bifurcated extension 23 which is pivot-
60 ally connected to knife 28 by pivot 27.
Sleeve 22 is slidably mounted in bearing 26.
Knife 28 is fulcrumed on pivot 29, as shown
in Fig. 3, and its sharpened end co-acts with
the knife edge 30 to shear the material when
65 the knife blade is operated. Knife edge 30
is affixed to guide plate 35 and guide plate
35 is secured to the top plate by bracket 34.
The shank of the knife 28 is provided with
an extension 31, to which is attached the
70 spring 32 which is in turn attached to a
bracket 33 whereby to normally hold the
knife in the open position illustrated in Fig.
3. The material to be severed consists of
strips of cotton N enclosed in a tubular
75 knitted fabric which is drawn through the
interior of tube T by the friction wheels 14
and 6, as shown in Fig. 1 and is fed over the
guide plate or platform 35 and over knife
edge 30. I may provide a modified cam 38
80 as shown in Fig. 5 which is provided with
the opposite projections 39 and 40.

In operation, in the event of a knot, ob-
struction, or one of the strips of cotton or
napkins ends comes under the knife 28 at 85
the time it operates, a spring 25 in sleeve 22
will allow the rod 21 to travel its full stroke
without forcing the knife blade into the ma-
terial, thereby allowing the knife blade to
swing to its uppermost position as soon as
90 the cam projection has passed the roller 19
and thus allow the knot or other obstruc-
tion in the material to pass on and the knife
will not be again operated until the cam has
again rotated to operating position. This 95
operation automatically protects the ma-
terial and prevents choking of the knife.
Less attention on the part of the operator
is required and stoppage of the machine is
not required for disengaging material from
100 the knife when knots or obstructions occur
in the material.

What I claim is:

In an automatic cutter for cutting tubular
gauze covering for sanitary napkins, the 105
combination of a knife-edge, a knife ful-

2
crummed on one end of said knife-edge and adapted to cooperate therewith to cut the material, a spring connected with the shank of the knife to normally hold the knife in open position, cam controlled means adapted to move the knife to a closed position at regular intervals, a cam, a roller riding on

said cam, a rod connected to the hub of said cam, a sleeve in which the rod is slidably mounted, said sleeve being operatively connected to the shank of the knife, and a spring contained within the sleeve and bearing on the end of the slidable rod. 10

CHRISTOPHER G. GUIGNARD.
